FLUID ACTUATOR

Alois Wicha, Dresden, Germany, assignor to
Erospha Inc., Brooklyn, N. Y., a corporation
of New York

Application May 27, 1933, Serial No. 673,244
In Germany February 20, 1933

18 Claims. (Cl. 103—133)

The present invention relates to fluid and liquid actuating devices and it particularly relates to pumps, compressors and the like.

Although the present invention will be particularly described in connection with liquid pumps it is to be understood that it may also be employed with spherical engines or other similar apparatus generally where a fluid or liquid is passed into a casing to cause a shaft or a mechanism to be actuated, the flowing fluid or liquid being the source of energy around and being forced into the spherical casing under substantial pressure and/or removed therefrom under subatmospheric pressure or vacuum.

15. I have found that certain pumps provided with casings having interior chambers of partial spherical contour and including oscillating impellers may be employed in replacement of or in lieu of reciprocating rotary and other pumps with substantially increased efficiency and at low cost, with substantial elimination of many of the disadvantages inherent in such rotary and reciprocating pumps and with an enhancement of many of the advantageous features associated therewith.

20. In one preferred form of my invention the interior chamber of the casing may take the contour of a spherical section or segment with a peripheral spherical surface and flat or conical side walls. An oscillating circular impeller is contained in said chamber, and the oscillating motion of this impeller is caused to take place both horizontally and vertically within said casing about a fixed centre by a drive shaft which 25 extends axially into the casing.

The drive shaft is provided with an eccentric driving bearing for the impeller causing this impeller to undergo said oscillating movement whereby fluid or liquid is continuously drawn in 30 through the inlet, moved through the casing, and ejected into the outlet through suitable ports in and at one side of the peripheral spherical surface.

In pumps, compressors or other liquid actuating devices of this character, it is necessary to provide means to separate the inlet and outlet ports and prevent transference of liquid or fluid therebetween except by the rolling oscillating movement of the impeller and also to provide 35 means for preventing the rotation of the impeller, while permitting it to undergo the oscillating movement aforescribed.

In separating the inlet from the outlet it has been found satisfactory to provide a partitioning 40 wall extending across one side of the interior

pump chamber between the side walls of said chamber, which wall may desirably be fixed with respect to the casing and extend through a slot in the oscillating impeller.

On the other hand, in guiding the motion of the impeller and permitting the rolling oscillation, it has been found desirable to utilize a pivotal element which bears both in the casing and in the impeller, and which will permit relative rotational movement and sliding of the impeller 10 in respect to the casing, and it is a particular object of the present invention to improve this guide member so that it will cooperate most efficiently with the impeller and function in a most desirable manner.

15. A further object of this invention is to provide a guide member and to so construct the impeller to cooperate with said guide member, that the amount of strain and friction will be reduced to a minimum, so that no cocking or biasing effect 20 will ensue, tending to place excessive strains either upon the impeller or the guide or tending to prevent ready relative rolling or sliding movement of said impeller and guide member.

25. Another further object of the present invention is to provide a guide member and to form an impeller member to cooperate therewith so that the oscillating movement of the impeller, or pump actuator, will take place in such a manner as to result in the highest degree of efficiency and substantially eliminate acceleration and deceleration 30 of the impeller masses during the operation of the pump.

35. Another object is to provide an impeller member which will most efficiently utilize its entire propelling surface for moving fluid or liquid from the inlet to the outlet of the pump during the oscillating movement thereof.

40. In accomplishing these last-mentioned objects it has been found most satisfactory to provide a guide member which may partake of a relative sliding movement, both with respect to the casing and the impeller. This guide element in one embodiment may take the form of a ball or roller key element which is guided and engaged in slots in 45 the wall of the casing and in the impeller structure.

50. In one embodiment of the present invention the impeller is composed of two frusto-conical wall sections which diverge toward the center point of the eccentric actuating bearing, the axes of which conical sections, however, are oblique to the central axes of the eccentric bearing and at an angle less than 180° to each other.

55. The above and other objects will appear more

clearly from the following detailed description, when taken in connection with the accompanying drawings which illustrate a preferred embodiment of the inventive idea.

5 In the drawings:

Fig. 1 is a side sectional view of the casing with the impeller in position therein.

Fig. 2 is a transverse front sectional view upon the line 2—2 of Fig. 1.

10 Fig. 3 is a top longitudinal sectional view of the casing upon the lines 3—3 of Fig. 2.

Fig. 4 is a front view of the impeller removed from the casing.

15 Fig. 5 is a side sectional view of the impeller removed from the casing.

Fig. 6 is a top view of the impeller removed from the casing.

Fig. 7 is a side view of the actuating drive shaft.

20 Fig. 8 is a top diagrammatic sectional view along the line 7—7 of Fig. 2, diagrammatically illustrating the relationship of the partitioning wall to the inlet and outlet ports and the impeller.

25 Fig. 9 is a side view in fragmentary section of the shaft and impeller wall insert and pumping chamber wall insert removed from the assembly shown in Figs. 1 and 2.

30 Figs. 10 to 18 are top and front views of the impeller illustrating diagrammatically the operation of the device of the present invention.

In Figs. 1 to 3 the casing A is provided with an interior chamber B of spherical contour, which chamber receives the impeller C. The opposite sides of the casing C are provided with the tubular projections or bosses D which contain the bearing sleeves M receiving the shaft E. The shaft E is centrally provided within the casing with a ball element F which has an oblique slot J receiving the impeller C.

40 The guide H, to which this invention is particularly directed, has bearings both in the casing A and in the impeller C and regulates the oscillating rolling movement of said impeller C. The partitioning wall I separates the inlet and outlet ports and prevents fluid or liquid from being transferred directly therebetween except by the oscillating movement of the impeller C.

45 The interior chamber B of the casing A (see Figs. 1, 2 and 3) is of a spherical contour having a peripheral wall 20.

50 As shown in Figs. 1, 3 and 9 the bearing sleeves M are provided with the cylindrical bearing metal liners 150 receiving the shafts E. The inner ends 55 of the sleeves M mushroom outwardly to form the spherical bearing sockets 23 for the opposite sides of the ball element F and are provided with the conical extensions 21 forming the side walls of the pumping chamber B within the casing A, upon which side walls 21 the impeller C rolls during its oscillating movement.

60 The side walls of the impeller C take the form of frusto-conical sections which converge toward the center point 22 of the pump structure, but which are obliquely located so that their axes are at an angle of less than 180° to each other, and are inclined to the horizontal axes of the shaft E.

65 One side of the casing A is provided with the extensions 24 and 25 (see Fig. 2) which have central openings 26 and 27, serving as inlet and outlet ports. These inlet and outlet ports 26 and 27 intersect the peripheral spherical surface 20 to form inlet and outlet elongated openings therein preferably of rectangular shape.

70 The inlet and outlet ports 26 and 27 are sep-

arated by the partitioning wall I which takes the form of an annular section and fits at its ends in slots 29, in the conical side walls 21 (see Fig. 8).

As a result direct communication between the inlet and outlet ports 26 and 27 will be prevented and all fluid or liquid will necessarily be transmitted through the casing A in the direction indicated by the arrow 30 on Fig. 2.

75 As shown in Figs. 1 and 7, the oblique slot J 10 in the central ball element F is provided with an oblique cylindrical central shaft element 31 and with inwardly converging frusto-conical side surfaces 32 which converge toward the center point 22 of the pump, which also is the center point 15 of the ball element B.

The impeller C is shown in the casing in Figs. 1 and 2 and removed therefrom in Figs. 4, 5 and 6.

80 The impeller has two outwardly diverging truncated or frusto-conical propelling plate sections 34, which inwardly converge towards said center point 22 and which are provided at their outer extremities with the peripheral spherical surfaces 20', which closely conform with the interior peripheral surface 20 of the interior chamber B.

85 It will be noted that the frusto-conical plate sections 34 (see particularly Figs. 4, 5 and 6) are provided with oblique axes corresponding to the axes of the wall sections 21 of the casing. The axes of the conical sections 34 are oblique to the horizontal axes of the impeller and to the axes of the eccentric shaft element 31 forming the base of the slot J in the ball F.

90 The central section of the impeller is formed by a spherical section 33 which at the lower side of the impeller merges into the frusto-conical section 34 and at the upper side of the impeller adjacent the inlet and outlet ports 26 and 27 project substantially beyond the side walls of 40 the impeller C. The central spherical impeller section 33 is provided with the bearing insert 133 which is of bearing metal and contacts with the surfaces 31 and 32 of the slot J. It will be noted that the side walls 32 of the central impeller section 33 converge toward the central point 22 of the impeller and that the axes of these converging walls 32 coincide with the central axes of the oblique shaft element 31 of the shaft E.

95 As indicated, the impeller is of two-piece construction having an upper section 150 and a lower section 151, which are joined together at 152 by the fins 153 and the bolts 154.

The impeller C being of hollow construction, as indicated, is of relatively light weight and results in a substantial decrease in the overall weight of installation.

100 The portion of the impeller C adjacent the inlet and outlet ports 26 and 27 is provided with a transverse slot 37 (see Figs. 4, 6 and 8) to receive the partitioning wall I. The bottom 38 of the slot 37 is formed by the spherical impeller section 33, which contacts with the correspondingly shaped surface 38' of the partitioning wall I. The upper side 39 of the partitioning wall I closely contacts with the spherical periphery 20 of the interior chamber B of the casing A.

105 The sides 40 of the partitioning wall 28 are 70 closely adjacent to the sides 40' of the slot in the impeller, the side walls of said slot in the impeller diverging outwardly as indicated so that it is possible for said impeller C to have a substantially rotary movement in respect to said 75

partitioning wall I without jamming or frictional contact.

The impeller C is provided with a ball guide member H which controls the oscillating movement thereof, preventing rotation with the rotation of the shaft E. The ball guide H, which is shown in combination with the impeller C and casing A in Figs. 1, 2 and 3, is received in a slotted insert 35, received in a recess 135 in the casing A and in a slotted element 36 received in a recess 136 in the impeller element C.

As shown in Figs. 1 and 2, the insert 35 in the recess 135 in the casing is provided with a spherical bearing surface 235 over which the spherical edges 20' of the impeller move. The ball guide H is received in the semi-circular groove or slot 35' in said insert 35.

The upper part of the ball fits into the corresponding semi-circular slot or groove 36' in the insert 36 in the recess 136 in the impeller. This recess is formed between the side walls 34 and the lower transverse wall interiorly positioned between said side walls 134.

The ball guide H, as shown in Figs. 1 to 3 will permit relative sliding and rotating movement of the impeller in respect to the casing A. As a result, the oscillating movement of the impeller C will cause all points on the surface 20' of the impeller C to undergo lemniscate movements of

varying amplitude. The amplitude of these lemniscate curves is maximum adjacent the horizontal axis of the casing A and decreases until such movement substantially resembles that of a straight line adjacent the upper and lower parts of the casing and particularly at the inlet and outlet ports 26 and 27 and the partitioning wall I.

The operation of the pump is most conveniently shown from the diagrammatic views, Figs. 10 to 18. Fig. 10 illustrates diagrammatically the turning of the impeller and Figs. 11 to 18 show top and front views of the impeller in each one of the positions designated on Fig. 10, namely I, II, III and IV.

Figs. 11 and 12 are, respectively, side and front views of the impeller in position I; Figs. 13 and 14 are corresponding views in position II; Figs. 15 and 16 are corresponding views in position III; and Figs. 17 and 18 are corresponding views in position IV.

From a consideration of Figs. 11 to 18 it appears when the shaft E rotates, the impeller C will be caused to sweep backwardly and forwardly both horizontally and vertically across the interior chamber B with the result that the impeller C will partake of a lateral oscillation.

At the same time the axes about which the impeller C tends to swing will also tend to rotate about the fixed common center point 22 of the casing A, impeller B and the impeller C. The horizontal axis of the impeller C and the oblique axes of the conical sections 34 will describe conical surfaces converging toward and having apices at the center point 22. The vertical axis will tend to swing in a vertical plane coinciding with the separating wall I.

As a result of this movement, as previously stated, all points on the periphery of the impeller C removed from the vertical axis will tend to move along lemniscate curves which become of greater latitude as the point approaches the horizontal axis of the impeller. These curves will lay in a spherical surface described upon a radius equal to the distance of the point from the center point 22. Because of this movement, substantial acceleration or deceleration forces will not be in-

curred upon movement of the mass of the impeller C and the abrupt changes in acceleration characteristic of the movement of the piston of a reciprocating pump are altogether eliminated.

As indicated in Figs. 11 and 12 respectively, in top and front views, the impeller C will divide the interior B of the casing A into two compartments 60 and 61, taking the shape of spherical wedges, which compartments are symmetrically disposed in respect to the center point 22.

In Figs. 11 and 12 the compartment 61 occupies the upper portion of the casing A, while the chamber 60 occupies the lower portion of the casing A. In Fig. 13 the compartment 60 occupies the right side of the chamber B while the compartment 61 occupies the left side of the chamber B.

In Figs. 15 and 16 the compartment 61 occupies the lower portion of the chamber B while the compartment 60 occupies the upper portion of the chamber B and in Fig. 17 the compartment 60 occupies the right side of the chamber B while the compartment 61 occupies the left side of the chamber B.

It is apparent that these wedge-like compartments 60 and 61, due to the oscillation movement of the impeller C, are caused to rotate continuously within the interior chamber B of the casing A.

These compartments 60 and 61 are successively opened and closed to the inlet 26 and to the outlet 27 so that fluid or liquid which is received through the inlet 26 will be carried to the outlet 27. These compartments 60 and 61 will transfer liquid or fluid through the lower half of the chamber B, the inlet 26 to the outlet 27 and will be prevented from transferring fluid or liquid reversely from the outlet to the inlet in the upper half of the chamber B by the wall I.

It will be noted in Figs. 11, 13, 15 and 17 that the compartments 60 and 61 must move through and will be divided by the wall I, said movement being in the direction of rotation of said shaft E. In Fig. 11 the compartment 61 is bisected by the wall I, while in Figs. 13 and 17 both compartments are divided by the wall I. In Fig. 15 only the compartment 60 is divided by the wall I.

As the compartments 60 and 61 rotate and pass through the wall I they are substantially continuously in communication with both the inlet 26 and the outlet 27. During the rotation of the shaft E and oscillation of the impeller C the volume of the compartments upon the outlet side of the wall will decrease, with the result that the liquid or fluid therein is discharged through the outlet. At the same time the volume of the chamber on the inlet side of the wall I increases with the result that liquid is sucked in through the inlet 26 to fill the increasing volume on that side.

It will thus be apparent that each compartment 60 and 61 as it passes through the wall 27 has inlet and outlet portions of changing volume separated by the areas or lines 62 and 63 and the wall I, the volume successively increasing in communication with the inlet and decreasing in communication with the outlet.

These areas or lines are indicated in Figs. 12, 14, 16 and 18 by the dotted lines 62 and 63. The areas or lines for the opposite compartments are always symmetrically disposed diametrically opposite each other in respect to the center point 22.

As soon as the last edges of the compartments 60 and 61 have passed the outlet port 27, the approaching edges of the same compartments will be opened to the outlet port. This occurs as the areas or lines 62 and 63 pass across the port 27.

45

50

55

60

65

70

75

The same also occurs in respect to the inlet port 26.

In the position shown in Figs. 11 and 12 the contact 62 coincides with the connection of the ends of the wall I with the wall 21 of the interior B so that the compartment 60 in this position is not divided nor is it decreased in volume by the volume of the wall. To reach this position the compartment 60 has been increased in volume 10 while in communication with the inlet 26 on the inlet side of the wall I, with the result that an amount of fluid or liquid equal in amount to the maximum volume of the compartment 60 has been sucked or drawn thereinto.

15 During this movement the edges 20ⁱ and 20° of the impeller C will swing across the ports 26 and 27 respectively and control the communication between them and the compartments 60 and 61.

20 As the shaft E continues to rotate and impeller C to move from the position of Figs. 11 and 12, to the position of Figs. 13 and 14, namely from position I to position II, as shown on Fig. 10, the upper edge 20° of the impeller C will tend to swing away from the wall 21 of the compartment 61 increasing the opening of the inlet and outlet 25 ports 26 and 27 to the compartment 60.

As this is occurring, the compartment 60 is being moved through the wall I so that it is increasing in volume in respect to the inlet port and decreasing in volume with respect to the outlet port 27.

In the position of Fig. 15 the compartment 60 is substantially bisected by the wall I and it is open one-half to the inlet 26 and one-half to the outlet 27 with the volume in communication with the inlet increasing while the volume with the outlet is decreasing. In this position the inlet and outlet ports will have their maximum opening to the compartment 60.

In Figs. 17 and 18 the contact area 63 has reached the position IV indicated in Fig. 10. In this position, the filling of the compartment 60 from the inlet 26 is being completed and the last 45 portions of liquid contained in said compartment 60 on the outlet side of the wall I are being forced out through said outlet 27.

As the compartment 60 then continues its rotational movement, the lower edge 20ⁱ of the impeller C will swing outwardly from the wall 21 of the compartment 61 permitting the incoming liquid to flow to the bottom of the interior of the chamber B in the compartment 60.

The operation of the other pumping compartment 61 is the same as has just been described, except that all operations take place 180° later or earlier than in the case of compartment 60.

It is, therefore, evident that as the shaft E rotates and the impeller C and the guide H oscillate, liquid or fluid will be continuously acted upon and moved from the inlet 26 to the outlet 27 by the compartments 60 and 61.

It will be noted that the guide H by fitting in the casing slot 35' and the impeller slot 36', respectively, will permit both lateral and vertical oscillation of the impeller C. In Figs. 13 and 17 the guide H will be in the middle portions of the slots 35' and 36', which cross each other obliquely in these positions. In Fig. 11 the guide H will be at the extreme left of the slot 35' and the extreme right of the slot 36'. In Fig. 15 the guide H will be at the right end of the slot 35' and at the left end of the slot 36'.

The guide H will slide readily through the slots 75 35' and 36' and will be lubricated in its motion

by the liquid being forced through the pump casting from the inlet 26 to the outlet 27. At the same time this guide H while permitting the oscillating movement of the impeller C will prevent rotary movement and will control the oscillating movement of the impeller C. All of this stress restraining the impeller C from rotating with the shaft E will be taken by pressure between the sides of the guide H and sides of the slots 35' and 36'. 10

It will be noted that the pump will substantially meter the flow. Except for a small amount of leakage across the periphery 20' and across the areas of the lines 62 and 63, the combined volume of the chambers 60 and 61 will be transferred 15 from the inlet to the outlet upon each complete revolution of the shaft E.

The volume of these pump compartments may be conveniently calculated by subtracting the volume of the impeller C and the ball F as well as 20 the wall I from the volume of the chamber B. The volume of these compartments control the capacity of the pump and its delivery per revolution and such volume is determined by the diameter of the chamber B and the width of such 25 chamber. The angle of the eccentric bearing slot J of the shaft E will vary with the width of the chamber B so that the impeller will contact the walls of such chamber in its oscillating movement. 30

The area of the inlet port 26 and the outlet port 27 should be always such that the compartments 60 and 61 may substantially immediately fill with liquid or fluid as they are increased in volume in communication with the inlet 26 and/or be emptied of fluid or liquid as they are decreased in volume in communication with the outlet 27. Otherwise, there would be a tendency for the impeller C, in the case of uncompressible liquids, to create a vacuum on the inlet side and to compress liquid on the outlet side, which would 40 reduce the efficiency of the pump. 35

The velocity of the movement of the body of the impeller C is substantially uniform at all times, there being no minimum or maximum velocity, merely a change in direction. 45

The axis of the eccentric slot shaft element 31, the axis of the impeller C and the vertical and horizontal axes of the interior B of the casing A, all intersect throughout movement at the common center point 22. The impeller is preferably so designed that its center of gravity coincides with this central point 22. 50

In considering the operation of the fluid actuating device of the present invention, which operation has been diagrammatically illustrated and described in connection with Figs. 10 to 18, it is to be noted that the impeller C in the course of its oscillating movement causes a displacement of fluid both when it moves toward the wall of the casing 21 and when it moves away from the wall of the casing 21. In the former case the fluid is forced out of the casing through the outlet or is forced from one part of the interior chamber B of the casing A to another part of the interior chamber Bi of the casing A, as indicated by the arrows 30. 55

Since the entire side wall or side propelling surface 34 of the impeller C does not move toward the side wall 21 of the interior chamber simultaneously but rather is caused to move over said surface so that one portion of the propelling face 34 of the impeller is advancing toward the side 21 of the casing, while another portion of the propelling face 34 of the impeller may be moving 70 75

away from the same side wall of the impeller, it is evident that the oscillating movement of the impeller C will result in moving fluid circularly around within the interior of the casing.

5 It is thus evident that the displacement action of the oscillating impeller C of the present invention differs substantially from the displacement action of the piston of a reciprocating pump in that whereas the motion of the reciprocating piston causes a linear movement of fluid to the end of a cylinder, in the device of the present application on the other hand, the displacement action of the impeller causes a rotational movement of the fluid from the inlet to the outlet along the 10 propelling face 34 of the impeller. The wall I extending between the side walls of the chamber causes the oscillation action to draw in fluid from the inlet and to force fluid out through the outlet.

The volume for containing fluid or liquid within 15 the casing of the device will always be substantially constant since it will be equivalent to the volume of the interior chamber B minus the volume of the impeller C and the volume of the wall I. As previously described, the impeller C will divide the chamber B into two symmetrically positioned pumping compartments 60 and 61 which, although they are of substantially constant volume throughout operation of the device (except for the volume of the wall I which may project into them) they nevertheless will have portions of varying volumetric capacity the portion in communication with the inlet increasing while the volume in communication with the outlet is decreasing.

35 From this point of view it may be considered that the wall I is a fixed fluid impelling device which moves relatively through the compartments on opposite sides of the impeller C to increase the volume of the compartments 60 and 61 on one side, causing drawing in of liquid from the inlet 20 and to decrease their volume on the other side, causing discharge of liquid through the outlet 27. This action, however, is quite different from the action of a reciprocating piston pump in which there is a fixed piston and a movable cylinder, in that in the present invention the displacement member or wall I moves continuously through the compartments, one after the other without the abrupt reversals as occur in all reciprocating 25 pumps.

It is apparent from the foregoing description of the operation, that the shaft may be rotated in either direction, and that as a result of such reverse rotation the inlet 26 and outlet 27 will be similarly reversed. The discharge output of the device is proportional to the speed of rotation of the shaft, while the head or height of delivery is independent of the speed of rotation.

Although the impeller is shown as formed of 30 two sections which are bolted together by the flanges 153 and the bolts 154 and the casing is also formed from two sections connected at the flanges 100 by the bolts 101 many other methods of construction might be employed, depending upon the 35 particular size and structure of the pump or other liquid actuating device. The foot 102 (see Figs. 1 and 2) serves as a means of attachment of the pump to a suitable support.

In Fig. 1 the shaft D is provided with a shoulder 40 104 which receives the bearing washer 105. The bearing washer 105 contacts and bears against the angular discs 106 which are pinned at 107 and 108 respectively to the cap 109 and to the tube projection D. The other end of the shaft E is 45 provided with the packing rings 111 which are

compressed by the cap 112 in the cavity 113 in the end of the tubular member D.

The impeller construction is particularly efficient inasmuch as the entire surface 34 will at all times be effective in propelling the liquid. The portions 170 (see Fig. 6) of the impeller will cover the inlet and outlet ports 26 and 27 at all times during the oscillating movement and will prevent bypassing of liquid between the plates 34 of the impeller. This bypassing of liquid will 10 also be prevented by the fins or flanges 153 which serve to carry the bolt connections 154 of the impeller heads.

The matter shown and described in the present application but not claimed herein is covered in 15 my copending applications Serial Nos. 656,637; 656,638; 656,639; 656,640 and 656,641, filed respectively Feb. 13, 1933; 673,245, filed May 27, 1933 and 696,944 filed Nov. 7, 1933. The copending applications 656,637; 656,639 and 656,641 show different types of impelling pistons which may be either outwardly convergent or divergent, or if desired provided with parallel side faces. The applications 656,637 and 656,639 show oscillating separating walls for separating the inlet and 20 outlet ports. 656,638 shows the employment of the device of the present invention as a gas compressor, while 656,641 shows this employment as a vacuum pump. Application 696,944 shows the provision of space or surface packing or sealing 25 between the peripheral and side surfaces of the impelling pistons and the peripheral and side surfaces of the interior chamber, which surface or space seal or packing is preferably utilized with 30 rotating side walls.

What is claimed is:

1. In a fluid pumping device, a casing having interior side walls and a continuous spherical end wall connecting said side walls, an impeller, the periphery of which closely conforms to the spherical end wall and oscillates vertically and horizontally with a rolling movement between said side walls and about the center point of said casing, a shaft passing into said casing having an eccentric cam member actuating said impeller, a ball 40 guide fitting into, and sliding within elongated slots in said impeller and casing, preventing rotation of said impeller while permitting the oscillating movement thereof, the axes of said shaft, said casing and said cam member intersecting at 45 said center point.

2. In a fluid actuating device, a casing having adjacent inlet and outlet ports, a fixed wall therebetween, an oscillating impeller having symmetrically connected truncated conical impelling surfaces, positioned in said casing, an eccentric driving shaft therefor and a ball guide for preventing rotation of the impeller, said shaft upon rotation causing a lateral and longitudinal oscillation of said impeller, the axes of said impelling 55 surfaces being set at an angle to each other and at an angle to the axis of said eccentric driving shaft.

3. In a fluid actuating device, a casing provided with adjacent inlet and outlet ports, a fixed 60 separating wall, an oscillating impeller closely fitting the walls of said casing and dividing the interior of said casing into a plurality of separated compartments, a drive shaft having an eccentric bearing in respect to said impeller and 65 a sliding ball guide preventing rotation but permitting oscillation of said impeller, the oscillation of said impeller causing a substantially continuous alternate successive opening and closing of said compartments to said inlet port and then 70

75 provided with the packing rings 111 which are

to said outlet port, whereby fluid will be continuously drawn in through said inlet and ejected through said outlet, said impeller being provided with annular frusto-conical side impelling surfaces, the axes of said surfaces being set obliquely to each other and substantially out of alignment.

4. In combination, a casing having an interior taking the form of a spherical section, and provided with an inlet port and an outlet port, an oscillating impeller therein, a shaft having an eccentric bearing for said impeller within said casing, and a guide connected to said impeller to prevent said impeller from rotating with the shaft, said impeller forming a plurality of symmetrical separated compartments in said casing and upon actuation by said shaft serving successively to open and close said compartments to said inlet and then to the outlet whereby fluid will be moved through said casing from said inlet to said outlet, said impeller being provided with annular impelling side surfaces formed of two opposite frusto-conical sections, the axes of which are oblique to the axis of the eccentric bearing, said impeller being arranged so that it will be relatively wide adjacent the guide and relatively narrow diametrically opposite said guide.

5. In a fluid pumping device, a casing having inlet and outlet ports, a relatively fixed partitioning wall therebetween, interior transverse conical side walls, the axes of which are oblique to each other and to the axis of the casing, and a continuous spherical end wall connecting said side walls, an impeller consisting of opposite frusto-conical propelling sections the periphery of which impeller closely contacts the spherical end wall and which impeller oscillates laterally and longitudinally between said side walls and about the center point of said casing, a shaft passing into said casing having an eccentric cam member actuating said impeller and a guide fitting in a slot in said impeller preventing rotation of said impeller with said shaft.

6. In a fluid actuating device, a casing having inlet and outlet ports, a separating wall between said ports, an oscillating impeller having conical side surfaces with obliquely disposed axes and a peripheral spherical surface, an eccentric driving shaft therefor and a guide for preventing rotation of the impeller with the shaft, said impeller and said casing being provided with slots to receive said guide, and said shaft upon rotation causing a lateral and longitudinal oscillation of said impeller, said conical side surfaces converging toward each other adjacent the wall and diverging on the diametrically opposite side of the impeller.

7. In a fluid actuating device, a casing provided with spaced inlet and outlet ports, a transverse fixed separating wall between said ports, an oscillating impeller closely fitting and contacting the walls of said casing and dividing the interior of said casing into a plurality of separated compartments, a drive shaft having an eccentric bearing in respect to said impeller and a ball guide preventing rotation but permitting oscillation of said impeller about a fixed center point, the oscillation of said impeller causing a substantially continuous successive opening, increase of volume, and closing of said compartments in respect to said inlet port and then a successive opening, decrease in volume and closing of said compartments in respect to said outlet port, whereby fluid will be continuously drawn in through said inlet and injected through said outlet, said impeller and said casing being pro-

vided with elongated slots to receive said ball guide, the portion of said impeller removed from said wall being laterally extended so as to receive one of said slots.

8. In combination, a casing having an interior taking the form of a spherical section with side walls, and provided with an inlet port and an outlet port, a transverse fixed separating wall between said ports, an oscillating impeller therein, a shaft having a ball with an eccentric bearing slot for said impeller, said ball being positioned in said casing, and a ball guide connected to said impeller to prevent said impeller from turning, said impeller forming a plurality of symmetrical separated chambers in said casing and upon actuation by said shaft serving successively to open and close said chambers to said inlet and then to the outlet whereby fluid will be moved through said casing from said inlet to said outlet, said impeller being provided with obliquely disposed conical propelling surfaces, the axes of said conical propelling surfaces being positioned out of alignment with each other and out of alignment with the axis of said eccentric bearing slot.

9. In a fluid actuating apparatus, a casing with inlet and outlet ports, a transverse fixed separating wall between said ports, an impeller therein, means to impart an oscillating movement to said impeller about a fixed center point, and a ball guide engaging said impeller and said casing to prevent rotation thereof while it is being oscillated by said means, said impeller being provided with an elongated slot to receive said ball and said casing being also provided with an elongated slot crossing said elongated slot in said impeller and also receiving said ball, said ball sliding in both of said slots during operation of said apparatus.

10. In a fluid actuator, a spherical enclosure, an impelling piston member extending across said enclosure, a fluid reaction member also extending across said enclosure, oblique holding means to hold said impelling piston member obliquely in respect to said fluid reaction member, whereby their opposing faces will diametrically oppositely approach and diverge from each other to form an annular-like wedge-shaped fluid receiving and discharging compartment, shaft means to undergo rotational movement with said oblique holding means, inlet and outlet connections to within said enclosure, guide means to prevent rotation of said piston member and to cause said impelling piston member and said fluid reaction member to undergo a relative lateral and longitudinal oscillating movement simultaneously with rotation of said oblique holding means and said shaft, whereby said wedge-shaped fluid receiving and discharging compartment is rotated into and out of communication with said inlet and outlet connections, said outlet and inlet connections being separated from each other and said compartment being divided into two sub-compartments, one of which increases in volume in communication with the inlet connection and the other of which decreases in volume in communication with the outlet connection during the rotation of the compartment, the side of said piston member being provided with an annular fluid propelling face, the axes of said oblique holding means of said fluid propelling face and of said shaft means being all set at substantial angles to each other.

11. In a liquid pump, a spherical casing including a peripheral spherical enclosure, a disc-like transversely slotted impelling piston member ex-

tending across said enclosure with annular frusto-conical propelling faces the apices of which frusto-conical faces are directed toward each other, conical side walls extending across and closing the sides of said enclosure, a central obliquely slotted ball to hold said impelling piston member obliquely in respect to said walls whereby said walls and faces diametrically oppositely approach and diverge from each other to form a plurality of annular-like wedge-shaped fluid receiving and discharging compartments extending laterally between said side walls and propelling faces and radially between said ball and said peripheral enclosure, shaft means to rotate said ball member rigidly connected thereto, inlet and outlet ports intersecting said enclosure, guide means in said slot in said piston member to prevent rotation of said piston member and to cause said impelling piston member to undergo a relative oscillating movement laterally in respect to and between said side walls upon rotation of said ball member by said shaft, whereby said wedge-shaped fluid receiving and discharging compartments are rotated into and out of communication with said inlet and outlet connections, said device being provided also with a transverse separating wall extending between said outlet and inlet ports passing through said transverse slot in said piston member and dividing each of said compartments during its rotation into two sub-compartments, one of which increases in volume in communication with the inlet connection and the other of which decreases in volume in communication with the outlet connection during the rotation of the compartments, the axes of said annular frusto-conical propelling faces, of said oblique slotted ball, and of said shaft means being set at substantial angles to each other.

12. In a liquid pump, a spherical casing including a peripheral spherical enclosure, a disc-like transversely slotted impelling piston member extending across said enclosure with annular frusto-conical propelling faces the sides of which frusto-conical faces are directed outwardly from each other, conical side walls extending across and closing the sides of said enclosure, a central obliquely slotted ball to hold said impelling piston member obliquely in respect to said walls whereby said walls and faces diametrically oppositely approach and diverge from each other to form a plurality of annular-like wedge-shaped fluid receiving and discharging compartments extending laterally between said side walls and propelling faces and radially between said ball and said peripheral enclosure, shaft means to rotate said ball member rigidly connected thereto, inlet and outlet ports intersecting said enclosure, guide means in said slot in said piston member to prevent rotation of said piston member and to cause said impelling piston member to undergo a relative oscillating movement laterally in respect to and between said side walls upon rotation of said ball member by said shaft, whereby said wedge-shaped fluid receiving and discharging compartments are rotated into and out of communication with said inlet and outlet connections, said device being provided also with a transverse separating wall extending between said outlet and inlet ports passing through said transverse slot in said piston member and dividing each of said compartments during its rotation into two sub-compartments, one of which increases in volume in communication with the inlet connection and the other of which decreases in volume in communication with the outlet connection during the rotation of the compartments, the axes of said annular frusto-conical propelling faces, of said oblique slotted ball, and of said shaft means being set at substantial angles to each other.

13. In a fluid actuator, a spherical enclosure, an impelling piston member extending across said enclosure, a fluid reaction member also extending across said enclosure, oblique holding means to hold said impelling piston member and said fluid reaction member obliquely in respect to each other, whereby their opposing faces will diametrically oppositely approach and diverge from each other to form an annular-like wedge-shaped fluid receiving and discharging compartment, shaft means to undergo rotational movement with said oblique holding means, inlet and outlet connections to within said enclosure, guide means to prevent rotation of said piston member and to cause said impelling piston member and said fluid reaction member to undergo a relative lateral and longitudinal oscillating movement simultaneously with rotation of said oblique holding means and said shaft, whereby said wedge-shaped fluid receiving and discharging compartment is rotated into and out of communication with said inlet and outlet connections, said outlet and inlet connections being separated from each other and said compartment being divided into two sub-compartments, one of which increases in volume in communication with the inlet connection and the other of which decreases in volume in communication with the outlet connection during the rotation of the compartment, said piston member being provided with a central transverse cylindrical face and with oppositely and symmetrically positioned outwardly diverging frusto-conical faces connected by said cylindrical face, said frusto-conical faces being set upon the same axis as the central cylindrical face and said cylindrical face and said frusto-conical faces cooperating with said oblique holding means, the fluid propelling faces of said piston member consisting of two exterior frusto-conical faces, the axes of which are oblique to each other and to the axis of said first-mentioned frusto-conical faces.

14. In a liquid pump, a spherical casing including a peripheral spherical enclosure, a disc-like transversely slotted impelling piston member extending across said enclosure with annular frusto-conical propelling faces, the bases of which frusto-conical faces are directed outwardly from each other, conical side walls extending across and closing the sides of said enclosure, a central obliquely slotted ball to hold said impelling piston member obliquely in respect to said walls whereby said walls and faces diametrically oppositely approach and diverge from each other to form a plurality of annular-like wedge-shaped fluid receiving and discharging compartments extending laterally between said side walls and propelling faces and radially between said ball and said peripheral enclosure, shaft means to rotate said ball member rigidly connected thereto, inlet and outlet ports intersecting said enclosure, guide means in said slot in said piston member to prevent rotation of said piston member and to cause said impelling piston member to undergo a relative oscillating movement laterally in respect to and between said side walls upon rotation of said ball member by said shaft, whereby said wedge-shaped fluid receiving and discharging compartments are rotated into and out of communication with said inlet and outlet connections, said device being provided also with a transverse separating wall extending between said outlet and inlet ports passing through said transverse slot in said piston member and dividing each of said compartments during its rotation into two sub-compartments, one of which increases in volume in communication with the inlet connection and the other of which decreases in volume in communication with the outlet connection during the rotation of the compartments, the axes of said annular frusto-conical propelling faces, of said oblique slotted ball, and of said shaft means being set at substantial angles to each other.

rotation of the compartments, the axes of said frusto-conical faces passing through the apices thereof, being set out of alignment so that they will be at angles to each other of substantially less than 180°.

13. In a fluid actuator, a spherical enclosure, an impelling piston member extending across said enclosure, a fluid reaction member also extending across said enclosure, oblique holding means to hold said impelling piston member and said fluid reaction member obliquely in respect to each other, whereby their opposing faces will diametrically oppositely approach and diverge from each other to form an annular-like wedge-shaped fluid receiving and discharging compartment, shaft means to undergo rotational movement with said oblique holding means, inlet and outlet connections to within said enclosure, guide means to prevent rotation of said piston member and to cause said impelling piston member and said fluid reaction member to undergo a relative lateral and longitudinal oscillating movement simultaneously with rotation of said oblique holding means and said shaft, whereby said wedge-shaped fluid receiving and discharging compartment is rotated into and out of communication with said inlet and outlet connections, said outlet and inlet connections being separated from each other and said compartment being divided into two sub-compartments, one of which increases in volume in communication with the inlet connection and the other of which decreases in volume in communication with the outlet connection during the rotation of the compartment, said piston member being provided with a central transverse cylindrical face and with oppositely and symmetrically positioned outwardly diverging frusto-conical faces connected by said cylindrical face, said frusto-conical faces being set upon the same axis as the central cylindrical face and said cylindrical face and said frusto-conical faces cooperating with said oblique holding means, the fluid propelling faces of said piston member consisting of two exterior frusto-conical faces, the axes of which are oblique to each other and to the axis of said first-mentioned frusto-conical faces.

14. In a liquid pump, a spherical casing including a peripheral spherical enclosure, a disc-like transversely slotted impelling piston member extending across said enclosure with annular frusto-conical propelling faces, the bases of which frusto-conical faces are directed outwardly from each other, conical side walls extending across and closing the sides of said enclosure, a central obliquely slotted ball to hold said impelling piston member obliquely in respect to said walls whereby said walls and faces diametrically oppositely approach and diverge from each other to form a plurality of annular-like wedge-shaped fluid receiving and discharging compartments extending laterally between said side walls and propelling faces and radially between said ball and said peripheral enclosure, shaft means to rotate said ball member rigidly connected thereto, inlet and outlet ports intersecting said enclosure, guide means in said slot in said piston member to prevent rotation of said piston member and to cause said impelling piston member to undergo a relative oscillating movement laterally in respect to and between said side walls upon rotation of said ball member by said shaft, whereby said wedge-shaped fluid receiving and discharging compartments are rotated into and out of communication with said inlet and outlet connections, said device being provided also with a transverse separating wall extending between said outlet and inlet ports passing through said transverse slot in said piston member and dividing each of said compartments during its rotation into two sub-compartments, one of which increases in volume in communication with the inlet connection and the other of which decreases in volume in communication with the outlet connection during the rotation of the compartments, the axes of said annular frusto-conical propelling faces, of said oblique slotted ball, and of said shaft means being set at substantial angles to each other.

connections, said device being provided also with a transverse separating wall extending between said outlet and inlet ports passing through said transverse slot in said piston member and dividing each of said compartments during its rotation into two sub-compartments one of which increases in volume in communication with the inlet connection and the other of which decreases in volume in communication with the outlet connection during the rotation of the compartments, said piston member being provided with a central cylindrical face and with symmetrically positioned outwardly diverging frusto-conical faces contacting with the face of said ball slot, said last-mentioned frusto-conical faces being inside of said frusto-conical propelling faces and being set on different axes than said frusto-conical propelling faces.

15. In a fluid actuator, a spherical enclosure, an impelling piston member extending across said enclosure, a fluid reaction member also extending across said enclosure, oblique holding means to hold said impelling piston member and said fluid reaction member obliquely in respect to each other, whereby their opposing faces will diametrically oppositely approach and diverge from each other to form an annular-like wedge-shaped fluid receiving and discharging compartment, shaft means to undergo rotational movement with said oblique holding means, inlet and outlet connections to within said enclosure, guide means to prevent rotation of said piston member and to cause said impelling piston member and said fluid reaction member to undergo a relative lateral and longitudinal oscillating movement simultaneously with rotation of said oblique holding means and said shaft, whereby said wedge-shaped fluid receiving and discharging compartment is rotated into and out of communication with said inlet and outlet connections, said outlet and inlet connections being separated from each other by a separating member and said compartment being divided into two sub-compartments, one of which increases in volume in communication with the inlet connection and the other of which decreases in volume in communication with the outlet connection during the rotation of the compartment, the maximum width of said compartment when it passes through said separation between the inlet and outlet connections being much greater than the maximum width of said compartment when it passes through a diametrically opposite portion of said enclosure.

16. In a liquid pump, a spherical casing including a peripheral spherical enclosure, a disc-like transversely slotted impelling piston member extending across said enclosure with annular frusto-conical propelling faces, the bases of which frusto-conical faces are directed outwardly from each other, conical side walls extending across and closing the sides of said enclosure, a central obliquely slotted ball to hold said impelling piston member obliquely in respect to said walls whereby said walls and faces diametrically oppositely approach and diverge from each other to form a plurality of annular-like wedge-shaped fluid receiving and discharging compartments extending laterally between said ball and said peripheral enclosure, shaft means to rotate said ball member rigidly connected thereto, inlet and outlet ports intersecting said enclosure, guide means in a second slot in said piston member to prevent rotation of said piston member and to cause said impelling piston member to undergo

a relative oscillating movement laterally in respect to and between said side walls upon rotation of said ball member by said shaft, whereby said wedge-shaped fluid receiving and discharging compartments are rotated into and out of communication with said inlet and outlet connections, said device being provided also with a transverse separating wall extending between said outlet and inlet ports passing through said transverse slot in said piston member and dividing each of said compartments during its rotation into two sub-compartments, one of which increases in volume in communication with the inlet connection and the other of which decreases in volume in communication with the outlet connection during the rotation of the compartments, the propelling faces of said piston member and said conical side walls being set in respect to each other so that said compartments will have a greater maximum width when passing through said enclosure and said separating wall than when they pass through said enclosure diametrically opposite to said separating wall. 10

17. In a liquid pump, a spherical casing including a peripheral spherical enclosure, a disc-like transversely slotted impelling piston member extending across said enclosure with annular frusto-conical propelling faces, the bases of which frusto-conical faces are directed outwardly from each other, conical side walls extending across and closing the sides of said enclosure, a central obliquely slotted ball to hold said impelling piston member obliquely in respect to said walls whereby said walls and faces diametrically oppositely approach and diverge from each other to form a plurality of annular-like wedge-shaped fluid receiving and discharging compartments extending laterally between said side walls and propelling faces and radially between said ball and said peripheral enclosure, shaft means to rotate said ball member rigidly connected thereto, inlet and outlet ports intersecting said enclosure, guide means in a second slot in said piston member to prevent rotation of said piston member and to cause said impelling piston member to undergo a relative oscillating movement laterally in respect to and between said side walls upon rotation of said ball member by said shaft, whereby said wedge-shaped fluid receiving and discharging compartments are rotated into and out of communication with said inlet and outlet connections, said device being provided also with a transverse separating wall extending between said outlet and inlet ports passing through said transverse slot in said piston member and dividing each of said compartments during its rotation into two sub-compartments, one of which increases in volume in communication with the inlet connection and the other of which decreases in volume in communication with the outlet connection during the rotation of the compartments, the annular frusto-conical propelling faces converging so as to be closely adjacent each other at the separating wall and diverging toward the opposite side of the enclosure, so that the lateral width of the piston member will be substantially greater adjacent the separating wall than at the diametrically opposite portion of the enclosure. 15 20 25 30 35 40 45 50 55 60 65 70 75 80 85 90 95 100

18. In a liquid pump, a spherical casing including a peripheral spherical enclosure, a disc-like transversely slotted impelling piston member extending across said enclosure with annular frusto-conical propelling faces, the bases of which frusto-conical faces are directed outwardly from 75

each other, conical side walls extending across and closing the sides of said enclosure, a central obliquely slotted ball to hold said impelling piston member obliquely in respect to said walls 5 whereby said walls and faces diametrically opposite approach and diverge from each other to form a plurality of annular-like wedge-shaped fluid receiving and discharging compartments extending laterally between said side walls and pro- 10 pelling faces and radially between said ball and said peripheral enclosure, shaft means to rotate said ball member rigidly connected thereto, inlet and outlet ports intersecting said enclosure, guide means in a second slot in said piston member to 15 prevent rotation of said piston member and to cause said impelling piston member to undergo a relative oscillating movement laterally in respect to and between said side walls upon rotation of said ball member by said shaft, whereby 20 said wedge-shaped fluid receiving and discharg-

ing compartments are rotated into and out of communication with said inlet and outlet connections, said device being provided also with a transverse separating wall extending between said outlet and inlet ports passing through said trans- 10 verse slot in said piston member and dividing each of said compartments during its rotation into two sub-compartments, one of which increases in volume in communication with the inlet connection and the other of which decreases 15 in volume in communication with the outlet connection during the rotation of the compartments, said guide means taking the form of a small ball, and said piston member and said spherical enclosure being both provided with elongated slots 20 to receive said ball, said slots extending respectively transversely across the piston member and across the spherical enclosure between said pro- pelling faces and between said conical side walls.

ALOIS WICHA. 20
